UNITED STATES PATENT OFFICE.

ALFRED HENRY McNEIL, OF CHINGFORD, ENGLAND.

THERMOSTATIC REGULATING OR CONTROLLING APPARATUS.

1,416,851.

Specification of Letters Patent. Patented May 23, 1922.

Application filed January 23, 1918. Serial No. 213,326.

To all whom it may concern:

Be it known that I, ALFRED HENRY McNEIL, a subject of the King of Great Britain and Ireland, whose post-office address is 5 "Manaton," Victoria Road, Chingford, Essex, England, have invented certain new and useful Improvements in Thermostatic Regulating or Controlling Apparatus, of which the following is a specification.

10 This invention relates to thermostatic regulating or controlling apparatus and has for its object to provide an improved apparatus capable of controlling fairly high temperatures ranging for example up to 1,000° F., 15 such apparatus being applicable for a variety of uses including the control of electrically heated induction pipes of engines employed on aircraft, muffles or muffle furnaces and various electric, gas, hot water 20 and other heating systems and apparatus.

The invention comprises an elongated thermo-sensitive member or tube fixed at one end and supporting by its other or free end a second elongated member to which longitudinal movement is imparted due to the 25 effects of changes of temperature on the elongated supporting member, such movement being transmitted to an electric contact, valve, or other controlling device. The 30 invention also comprises electrical controlling means.

According to this invention a thermo-sensitive member consisting of a tube or sleeve made of metal having a high co-efficient 35 of expansion is fixed at one end and free at the other end, and a rod or tube made of metal or other material having a lower co-efficient of expansion is fixed at one end to the free end of the metal tube and 40 extends freely within the tube in the direction of the fixed end of the said tube where it operates on a movable electric contact, valve or other device.

An electrical system of control co-operating 45 with the thermo-sensitive device and designed to open and close a switch in the circuit of an electrical heating apparatus, includes a pivoted switch arm with controlling coil or relay, a pivoted locking arm for the 50 switch arm also with controlling coil, and electrical circuits controlled by a movable contact co-operating with two fixed contacts for energizing and de-energizing the coils.

55 The switch is closed by the action of its coil upon the closing of a circuit by the

movable contact operated by the thermo-sensitive member, and automatically locked in the closed position by the locking arm, the said switch being released and moved 60 into the open position under the action of a spring by the closing of another circuit by the same contact member which is moved from the switch closing contact to a switch opening contact under the action of the 65 thermo-sensitive device as the temperature rises.

In order to prevent sparking the controlling circuits of both the switch arm and switch locking arm are broken automatically 70 as soon as their coils have operated the said arms, by carbon contacts carried on and moving with the arms themselves, the contact carried on the switch arm operating in the circuit of the locking arm and the contact on the locking arm operating in the circuit of the switch arm, the locking arm being held up in the in-operative position by the switch arm, and moved into the locking position by a spring or other means when the 80 switch is closed. Other means of controlling the opening and closing of the heating circuit by the thermo-sensitive device may be adopted. In the case of gas heated apparatus the movable member of the thermo- 85 stat may operate directly upon a valve for turning on or shutting off the supply.

When the invention is applied to the induction pipe of an aircraft engine heated electrically the pipe is provided with a 90 chambered cap having a removable cover. Within the chamber is mounted a blade carrying an adjustable screw with pointer movable over a dial and a movable contact arranged eccentrically of the screw and co-operating with a fixed contact in the controlling circuit.

In the accompanying drawings:—

Fig. 1 is a longitudinal section through an induction pipe fitted with a thermostatic 100 device constructed according to the invention and also shown in section,

Fig. 2 is a plan of the same with the cover removed,

And Figs. 3 and 4 are diagrams of electrical systems of control co-operating with the thermo-sensitive member.

Referring first to Figs. 1 and 2 which clearly illustrate the thermostatic contact making or breaking device, a tube *a* of brass 110 or other metal with a high co-efficient of expansion is fixed at one end only and en-

closes a rod *b* of metal or other material having a lower co-efficient of expansion than the metal of the tube *a* the rod *b* being screwed into or otherwise fixed at one of its ends to the free end of the tube *a* as shown, whilst the other end of said rod freely projects from the tube and bears against an adjusting screw *c* carried on a movable contact blade such as *d* hereafter more fully described. As previously described the rod *b* may be employed to operate a valve or other control device instead of an electric contact.

When the thermostat is employed to control an electrical heating apparatus it may be arranged to control an electric circuit containing a relay for actuating a switch in the heating circuit.

Such a circuit is shown in the diagram Fig. 3, in which the thermostat is indicated by its tube *a*. The switch *s* controlling the heating circuit *e* is held in the closed position against the pull of a spring *s¹* by a relay *f* in a normally closed energizing circuit *g* supplied with current from a battery or from the main supply circuit. A second relay *f¹* in an earthed circuit *h* containing the contacts *d d¹* controlled directly by the thermostat, is arranged to open the circuit *g* when the circuit *h* is closed by the thermostat thus de-energizing the relay *f* and permitting the spring *s¹* to open the switch *s*. A stop for limiting the opening movement of the switch is indicated at *s²*. Suitable resistances placed on the respective circuits *g, h* are indicated at *r r¹*. *i* indicates a blow-out in the heating circuit.

A modified combined thermal and electrical system of control for an electrical heating apparatus according to this invention is illustrated in Fig. 4. Here again the switch *s* which is shown in the open position is closed by a coil or relay *f* but is locked in the closed position by a locking arm *j* with controlling relay *k*, the energizing circuits of the two relays *f—h* being controlled by the movable contact blade *d* actuated by the thermostat and moving between opposed fixed contacts *d² d³*. In the position shown the movable contact *d* being moved away from contact *d³* the circuit of the relay *f* is broken and the switch *s* pulled open by the spring *s¹* the locking bar *j* having previously been raised against the action of a spring *j¹* by the closing of the circuit of relay *k* through the contact *d²*. Before contact can be made between *d* and *d³* circuit of relay *k* is first broken but the locking arm *j* is held up by the switch *s* until the contacts *d d³* close the circuit of relay *f* to move the switch *s* into the closed position when the arm *j* is forced to move into the locking position against a stop *j²* under the influence of the spring *j¹*. In this case sparking at the contacts is prevented

by automatically opening the controlling relay circuits immediately the switch arm or switch locking arm has been operated by its respective relay, by movable carbon contacts *l m* carried on said arms co-operating with similar fixed contacts *l¹ m¹*. It will be seen that the contact *l* carried on the arm of switch *s* operates in the circuit of the locking arm relay *k* while the contact *m* on the locking arm operates in the circuit of the switch relay *f*.

Referring again to Figs. 1 and 2 which show the application of the thermostat to the induction pipe *n* of an aircraft engine for controlling electrical heating means, a chambered cap *o* is screwed on the pipe and closed by a removable cover *o¹*, the electric leads being taken into the chamber through insulating bushings *p*. The blade *d* carrying the adjusting screw *c* also carries a dial *c¹* over which a pointer on the screw is set to adjust the position of a contact *d²* carried on the blade in relation to a fixed contact *c²* in the controlling circuit of the heater.

The tube *a* of the thermostat is screwed at one end into the inner wall *o²* of the chambered cap *o* and encloses the other member, in this case the rod *b*, which projects from the tube through the said wall into the chamber of the cap in line with the screw *c* on the contact blade *d* and by bearing against the screw normally separates the contacts. When however the temperature in the induction pipe exceeds a predetermined limit the thermo-sensitive tube by its expansion lowers the rod sufficiently to close the contacts thus closing the controlling circuit which opens a switch in the heating circuit.

What I claim and desire to secure by Letters Patent is:—

In apparatus of the class described, a thermo-sensitive member fixed at one end, a rod connected to said member and to which longitudinal movement is imparted by the expansion and contraction of said member, a normally open electric circuit including a relay and also including a contact blade normally held in open position by said rod, an electric switch controlled by said relay, a locking bar for said switch, a spring to move said locking bar to locking position, a relay to move said bar to unlocking position, a circuit in which said relay is included, said circuit also including a contact against which said blade is normally closed, a contact on the locking bar and in the circuit in which the first named relay is included, and a contact on the switch and in the circuit in which the second named relay is included.

In testimony whereof I have affixed my signature.

ALFRED HENRY McNEIL.
